A. J. LLOYD

LOOSE LEAF BINDER

Filed Nov. 10, 1927

Inventor:
Arthur J. Lloyd,
By Dyer & Co., Chitton & Riley,
Attys.

UNITED STATES PATENT OFFICE.

ARTHUR J. LLOYD, OF OAK PARK, ILLINOIS, ASSIGNOR TO W. G. LLOYD COMPANY, OF CHICAGO, ILLINOIS, A CORPORATION OF ILLINOIS.

LOOSE-LEAF BINDER.

Application filed November 10, 1927. Serial No. 232,336.

This invention relates particularly to looseleaf binders of the type employing flexible chain-posts and suitable take-up mechanism for purpose of adjustment.

5 The primary object of the invention is to provide simple and improved extension means for the chain-posts in binders having only one of the clamping-members equipped with take-up mechanism.

10 The invention is illustrated in its preferred embodiment in the accompanying drawing, in which—

Fig. 1 is a sectional view of a loose-leaf binder embodying the invention, the section 15 being taken in a plane parallel with the rear end of the binder, as indicated at line 1 of Fig. 4; Fig. 2, an enlarged section taken as indicated at line 2 of Fig. 1; Fig. 3, a perspective view showing one of the post-guides 20 with which one of the clamping-members of the binder is equipped at its inner side; Fig. 4, a broken sectional view taken as indicated at line 4 of Fig. 1, it being understood that this view is parallel with one side of the 25 binder; and Fig. 5, a broken sectional view taken as indicated at line 5 of Fig. 1, but showing the condition when the insert post-sections shown in Fig. 1 are omitted and the chain-posts are connected directly to the 30 rigid post-sections which are permanently mounted on the clamping-members which are not provided with take-up mechanism.

In the construction illustrated, A and B 35 designate the clamping-members of a loose-leaf binder; C designates take-up mechanism housed within the clamping-member A; D, D designate flexible chain-posts having portions housed in the clamping-member A and connected with the take-up mechanism thereof; E, E designate post-sections 40 permanently swiveled on the clamping-member B; and F, F designate insert post-sections which may be inserted between the swiveled post-sections and the adjacent ends 45 of the chain-posts.

It is preferred to make the clamping-members A and B both hollow. Preferably, each clamping-member is formed integrally from a piece of sheet-metal which is folded 50 upon itself and provided with a hinge-eye at 1. One member of the folded metal is bent inwardly to provide the inner edge-wall 2, and then at right angles to provide one portion 3 of the inner side-wall of the clamping-member. The other portion of the folded

metal is extended, as indicated, to provide the outer side-wall 4 and the rear edge-wall 5 of the clamping-member. The metal is then bent to provide a flange 6 which constitutes a part of the inner side-wall of the 60 clamping-member and which is separated from the edge of the flange 3 by a longitudinal space 7.

In the case of the clamping-member A, the slot 7 is bridged by stirrups 8 which are 65 spot-welded to the flanges 3 and 6 and which support curved post-guides 9 which have inwardly curved portions 9^a which extend through the slot 7.

The take-up mechanism C preferably consists of a right and left threaded rod 10 whose ends are swiveled in interior fittings 11 with which the hollow bar A is provided near its ends; and nuts 12 slidably mounted within the member A and having secured 75 thereto at points 13 the adjacent links of the chain-posts.

The nuts 12 are provided with tapped perforations through which the screw-rod works. The extremities of the clamping-member A are equipped with caps 14, one 80 of which is provided with a perforation 14^a through which a key may be inserted. The adjacent end of the screw-rod is provided with an angular shank 15 adapted to receive 85 the key.

The chain-posts D may be of any suitable construction. In the illustration given, each post comprises a series of links 16 of approximately circular cross-section, but provided at their inner sides with slots; and a 90 series of smaller links 17 housed in said slots and connecting the links 16.

The free end-link 18 of each chain-post is provided with a threaded stud 18^a which is 95 adapted to be interlockingly connected with the corresponding swiveled socket member E, or with an insert post-section F, as may be desired.

The hollow clamping-member B is shown 100 provided with post-bases 19 which are located within the hollow body. These post-bases are shown as U-shaped sheet-metal members extending across the slot 7 of the member B and secured to the flanges 3 and 105 6 by means of spot-welding.

The preferred manner of securing the swiveled post-sections E to the bar B is by riveting a heavy stud 20 to the post-base 19. The stud 20 extends inwardly toward the 110

bar A and is provided with a peripheral groove which is engaged by an inturned flange 21 with which the swiveled post-section E is provided. The post-section E is shown as an interiorly threaded sleeve having a socket-member 21^a which is adapted to engage either the socket-member 18^a of the chain-post, or a corresponding socket-member of the insert post-section F.

10 The insert post-section F is provided with threaded socket-members 22 and 23, the former being adapted to screw into the socket-member 21^a and the latter being adapted to screw onto the socket-member

15 18^a.

In practice, cover-sections (not shown) usually are connected with the hinge-eyes 1 by means of suitable pintles. It will be understood that in the use of the binder, 20 the insert post-sections F are not employed until it is desired to expand the capacity of the binder beyond the capacity normally afforded by the flexible posts in connection with the take-up mechanism. When, however, the accumulation of leaves in the binder becomes sufficiently great to warrant the introduction of the insert post-sections, such sections may be inserted, it being understood that any desired number of interchangeable 25 post-sections F may be supplied with each binder.

When the leaves are in the book, assuming the insert post-sections to be employed, access to the swiveled post-sections E cannot be had without first employing a key to actuate the take-up mechanism in a direction to extend the flexible posts. After such extension, the leaves can be shifted towards the clamping-member A, thereby giving access 30 to the swiveled post-sections for the purpose of enabling insert post-sections to be introduced. Inasmuch as the clamping-member is an integral member with an intact outer side-wall, there is no chance for access 35 to the swiveled post-section, except by manipulating the take-up mechanism in the clamping-member A, which requires the use of a key. It will be understood, therefore, that there is an advantage in having the 40 swiveled members E mounted on the clamping-bar B through the medium of the studs, or short posts 20. This arrangement obviates the danger of an unauthorized person being able to press the leaves toward the top 45 clamping-bar A in such a manner as to give access to the swiveled post-sections.

The construction described is extremely simple and thoroughly adapted to the purpose. The binder can be extended to any 50 desired capacity by the use of insert post-sections and a single take-up mechanism will suffice.

The connections between the swiveled post-sections and the flexible chain-posts, or 55 between the insert post-sections and the

swiveled post-sections on the one hand, and the chain-posts on the other hand, must be interlocking connections capable of withstanding the pulling force exerted by the take-up mechanism when the clamping members are drawn together to clamp the leaves. Screw connections are best adapted to the purpose.

The foregoing detailed description has been given for clearness of understanding 75 only and no unnecessary limitations should be understood therefrom.

What I regard as new, and desire to secure by Letters Patent, is:

1. In combination in a binder, a hollow 80 clamping-member having take-up mechanism mounted therein and having post-guides at its inner wall, flexible chain-posts having portions within said clamping member connected with said take-up mechanism 85 and having portions extending through said guides and equipped at their free extremities with coupling-members, and a companion clamping-member having short inwardly extending post-sections permanently mounted 90 thereon and equipped with swivel coupling members interlockingly engaging said first-named coupling members.

2. In combination in a binder, a hollow 95 clamping-member having take-up mechanism mounted therein and having post-guides at its inner wall, flexible chain-posts having portions within said clamping-member connected with said take-up mechanism and having portions extending through said 100 guides and equipped at their free extremities with coupling-members, a companion clamping-member having short inwardly extending post-sections permanently mounted thereon and equipped with swivel coupling members interlockingly engaging said first-named coupling-members, and insert post-sections adapted to be inserted between the swiveled post-sections and the adjacent ends 11 of said chain-posts and having socket-members adapted to interlockingly engage the coupling-members of the swiveled post-sections and the chain-posts.

3. In combination in a binder, a hollow 110 clamping-member having a right and left threaded screw mounted therein and having also at its inner side a pair of post-guides, nuts on said screw-rod, chain-posts extending through said guides and having portions in said clamping-member connected with 115 said nuts, the free ends of said chain-posts having reduced threaded portions, and a companion clamping-member having short posts rigidly secured thereto and interiorly threaded tubular members swiveled on said short posts and screwed onto said threaded extensions.

4. In combination in a binder, a hollow 120 clamping-member having a right and left threaded screw mounted therein and hav-

ing also at its inner side a pair of post-guides, nuts on said screw-rod, chain-posts extending through said guides and having portions in said clamping-member connected with said nuts, the free ends of said chain-posts having reduced threaded portions, a companion clamping-member having short posts rigidly secured thereto and interiorly threaded tubular members swiveled on said 10 short posts and screwed onto said threaded extensions, and insert post-sections having at one end reduced threaded extensions and at the other end interiorly threaded socket-members, said insert post-sections being 15 adapted to be introduced between said chain-posts and said swiveled tubular members.

5. A binder comprising a hollow clamp-

ing-member equipped interiorly with take-up mechanism and provided at its inner side with post-guides, chain-posts extending 20 through said guides and connected with said take-up mechanism, said chain-posts having terminal links equipped with reduced threaded extensions, a companion hollow clamping-member provided at its inner side 25 with a longitudinal slot, post-attaching plates within said last-named member bridging said slot and secured to the inner sidewall of the member, short posts fixedly secured to said plates, and interiorly threaded 30 sleeves swiveled on said short posts and adapted to screw onto the threaded extensions of said chain-posts.

ARTHUR J. LLOYD.
